ATTORNEYS

UNITED STATES PATENT OFFICE.

ISAAC WILLIAM FRIEDMAN, OF NEW YORK, N. Y.

SYRINGE.

Application filed December 8, 1921, Serial No. 520,930. Renewed January 30, 1926.

This application is a renewal of prior application filed by me December 8, 1921, Serial Number 520,930 for syringes allowed June 19, 1924, and relates more particularly to improvements in dilating vaginal syringes.

The objects of the invention are to provide a device of this character in which the dilating fingers may be more readily and rapidly operated; to provide an arrangement of fingers by which their effectiveness will be increased to securely but detachably mount said fingers in the body portion; to provide a removable tip; to provide improved means for spraying the water or other fluid; to secure simplicity of construction and operation and to obtain other advantages and results as may be brought out in the following description.

20 Referring to the accompanying drawing in which like numerals of reference indicate similar parts throughout the several views;

Figure 1 is a side elevation of a syringe constructed in accordance with the present invention, and showing the fingers in retracted normal position;

Figure 2 is a similar view of the outer end of said syringe but showing the fingers in extended or dilated position;

30 Figure 3 is a longitudinal sectional view of the end of the syringe showing the tip and water outlet;

Figure 4 is a transverse sectional view on line 4—4 of Figure 2;

35 Figure 5 is a longitudinal sectional view of the body portion showing the fingers in normal position;

Figure 6 is a side elevation of one of said fingers removed from the body portion and 40 in normal position;

Figure 7 is a cross sectional view of the same on line 7—7 of Fig. 6;

Figure 8 is a view similar to Fig. 6 but showing the finger extended.

45 Figure 9 is a cross-sectional view on line 9—9 of Fig. 8, and

Figure 10 is a sectional view of the metallic ring on which the rubber portion of the finger is carried for mounting the same in 50 the body position.

In the specific embodiment of the invention illustrated in said drawings, the reference numeral 1 indicates the body of my improved syringe at one end of which is a connection 2 for introduction of water and a

connection 3 for the introduction of air or other fluid pressure as by means of bulb 4. The said body portion is an elongated structure as usual in this class of device, and preferably comprises a single piece of material such as moulded rubber in the outer end of which is secured a removable tip 5. As shown in the drawings, the body portion is centrally channelled, as at 6, for passage of water from the connection 2 to the outer end of the device. The tip 5 is shown as screw threaded at its inner end for attachment with corresponding screw threads in the end of the body portion, and the channel 6 communicates directly with the interior chamber 7 of said tip from which water may be sprayed through a plurality of suitable holes 8.

In the construction shown, means are provided for spraying the water in opposite directions, this constituting one of the features of the present invention. To accomplish the desired result, the cap is arranged so its edge next the body portion is spaced slightly therefrom so as to provide a circumferential gap through which the water may escape. The circumferential end walls bounding this gap are sloped for a short portion of the circumference in one direction, and for a short adjacent portion of the circumference they are sloped in another direction and so on alternately for the entire circumference. This alternate sloping of the walls of the body portion and tip gives a serrated or toothed appearance to the crevice or gap between 85 these two parts, as clearly illustrated in Figures 1, 2 and 3.

Adjacent the removable tip 5, I provide a plurality of extendible fingers 9, preferably arranged in staggered relation to each other about the body portion and arranged and adapted to be extended or dilated and retracted as occasion requires. These fingers are so constructed that in their normal position they are retracted and are only extended upon positive application of pressure within. Furthermore, the said fingers 9 are so constructed as to normally fold and occupy only a very short depth, the wall of each finger doubling within itself. By this construction, the space under the finger is open so the air or other fluid pressure may act upon the entire area of the finger immediately, thus facilitating the rapid operation of the finger. In order to remove and 100

attach the finger in position I have shown the same as constructed with a metallic ring 10 screw threaded on its exterior, as at 11, for engagement with corresponding screw 5 threads in the openings in the body portion of the device. In order to obtain a secure attachment of the rubber finger to the said metallic ring, the said ring preferably has a plurality of holes 12 through which the 10 rubber may knit together.

Within the body of the device I preferably provide an air or fluid chamber 13 beneath the several fingers in communication therewith so that as pressure is introduced 15 into said chamber 13 it will act simultaneously upon all of the fingers to extend the same. This air chamber 13 is entirely separated from the water channel 6, it being clearly shown in Figures 4 and 5 as positioned around said water channel but separated therefrom by an intervening tube-like wall 14. Air or other fluid pressure is introduced into said chamber 13 from the connection 3 by means of any suitable passage 15 of a size and shape sufficient for the 20 purpose.

Attention is called to the fact that the exterior of the device is fluted, there preferably being a flute 16 extending longitudinally 25 of the device to each of the fingers. Furthermore, the flute 16 in line with the finger closest to the end of the device extends to a position between the other two fingers, thus obtaining a better discharge of the fluids along the exterior of the device.

Obviously detail changes and modifications may be made in the construction of my 30 improved syringe, and I do not wish to be understood as restricting myself to the 40 exact structure shown except as set forth in

the following claims when construed in the light of the prior art.

Having thus described the invention, I claim:—

1. In a syringe, a body portion having a 45 fluid channel, and having a fluid chamber separated from said fluid channel, extendible fingers in communication with said chamber whereby pressure in said chamber will dilate said fingers independently of the fluid pressure in said channel.

2. In a device of the character described, a finger having a base, side wall, and tip, the tip normally folding within said side wall and said side wall normally folding within the base whereby the normal length 55 of the finger is substantially its minimum length.

3. A syringe comprising a fluted body portion, fingers adjacent the end of said body portion in staggered relation to each other, the outer ends of alternate flutes extending to a position between alternate fingers.

4. In a syringe, a body portion having a 65 fluid channel, and having a chamber separated from said fluid channel with a plurality of openings from said chamber to the exterior of the body portion, means normally retracted in said chamber and openings and extendible out of said openings laterally of 70 said body portion by pressure communicated within the chamber, and means for applying pressure within said chamber from a point exterior to said body portion and forcing 75 said extendible means out through said openings.

In testimony whereof I affix my signature.

ISAAC WILLIAM FRIEDMAN.
